INVENTOR
W. E. DALY

By Arthur F. Durand Atty.

UNITED STATES PATENT OFFICE

WILLIAM E. DALY, OF BENTON HARBOR, MICHIGAN

BERRY BOX CRATE

Application filed November 1, 1930. Serial No. 492,637.

This invention relates to the class of wooden receptacles and pertains particularly to crates designed for carrying a plurality of berry boxes.

5 The primary object of this invention is to provide an improved type of berry box crate carrying more than one tier of boxes having box spacing racks therein each designed to be held from contact with or pressing down

10 upon the layer of berry boxes therebeneath.

In berry box crates of the type at present in use spacing racks are provided for separating the layers of boxes but these racks rest upon the tops of the boxes, therefore the bottom layer of boxes must support the entire weight of the two layers thereabove and in addition to this if the berries in the boxes project above the tops thereof, the racks press down upon and mash them.

20 In the crate embodying the present invention the center and end head frames are provided with slats so positioned that when the frames are in place the top edges of the slats will come in a plane above the tops of the adjacent layer of boxes and the separating racks are designed to be inserted lengthwise of the crate through the head frames and to overlie and rest upon these slats, the ends of the racks being provided with cleats which position

30 against the outer faces of the slats and prevent their shifting longitudinally after being placed in position. With a crate of this character no one of the layers of berry boxes supports other boxes, therefore, no mashing

35 of the fruit can take place.

In addition to this the construction of the crates is such that the same are better ventilated than the present type of crate, where broad slats are placed across the ends as well as longitudinally of the sides so that when the crates are stacked in crossed relation in the usual manner the circulation of air therethrough will not be interfered with.

40 A further object of the present invention is to provide a crate which can be economically constructed and will be efficient for the purpose set forth.

The invention will be best understood from a consideration of the following detailed description taken in connection with the accom-

panying drawings forming a part of the present invention with the understanding, however, that the invention is not confined to any strict conformity with the showing of the drawings but may be changed or modified so long as such changes or modifications mark no material departure from the salient features of the invention as expressed in the appended claims.

55 In the drawings:—

60 Figure 1 is a longitudinal sectional view taken horizontally through a crate constructed in accordance with the present invention;

65 Figure 2 is a sectional view taken substantially upon the line 2—2 of Figure 1.

70 Referring to the drawings in detail wherein like numerals of reference indicate corresponding parts throughout the several views, the numeral 1 indicates the end head frames of a berry box crate of the character embodying the present invention, a center head frame arranged between and parallel with the end head frames being indicated by the numeral 2. Crates of this type having two sections divided by a central frame are commonly known as twenty-four, or "American" 75 quart crates.

76 These head frames are of rectangular formation and are connected by the side and bottom slats 3 and 3' respectively, which slats are relatively broad, as shown.

80 Each of the end heads 1 has a pair of narrow slats 4 secured across its inner face in the manner shown and the central frame has a pair of slats 5 extending transversely thereof between its side bars. The height of the slats 4 and 5 is such in the set-up crate, that when a layer of berry boxes is placed in the bottom of the crate upon the bottom slats 3' the top edges of these slats 4 and 5 will be in a plane above the tops of the berry boxes.

85 Designed to extend longitudinally through the crate through the center head frame 2 and overlying and resting upon the bars 5 thereof, are the box supporting racks, indicated generally by the numeral 6. These racks are each made up of two or more slats 7 ar- 90

95 100

ranged in side by side relation and connect-
ed across their ends by the cleats 8.

In packing the crates after the first or
bottom layer of berry boxes is placed in posi-
tion, these boxes being indicated by the nu-
meral 9, one of the racks is extended longi-
tudinally through the head frames thereof
over the lower ones of the rack supporting
slats 4 and 5, until the rack is in such a
position that when lowered, the cleats 8 upon
the ends thereof, will each engage the outer
face of a slat 4.

The slats 7 of the rack are then supported
upon the head frame slats 4 and 5 and the
cleats engaging the slats 4 of the end frames
in the manner shown prevent longitudinal
movement of the rack through the crate. The
berry boxes being of less height than the top
edges of the slats 4 and 5 are thus free from
contact with the rack overlying them and
when a second layer of boxes is placed in the
crate, the first or bottom layer will not carry
any of the weight of the second layer. After
positioning the second layer in the crate the
second rack is inserted in the same manner
as described in connection with the first rack
so that a third or top layer of boxes can be
placed in the crate in the usual manner.

The top slats 10 are secured across the
top bars of the head frames of the crate in
the manner shown.

From the foregoing description it will be
readily seen that berry box crates of the char-
acter herein described may be economically
constructed as all of the outside slats may be
made of the same size and the head frames
may be made of uniform construction thus
making it necessary to perform only two
operations previous to the assembling of the
crate that is, the making of the frames and
the cutting of the slats.

Thus the strips 7 and the cleats 8 constitute
horizontal shelves or partitions, for support-
ing one or more upper tiers of loaded boxes
or receptacles, in the manner shown. Each
horizontal shelf or partition is insertable
endwise, in a horizontal plane, through the
opening 10 in either end of the crate, and
through the openings 11 in the middle ver-
tical partition 2 of the crate. In removing
the loaded boxes or receptacles, below any
shelf or horizontal partition, the latter, after
the boxes above it are removed, is then re-
moved horizontally and longitudinally, in
the same horizontal plane, through the said
openings 10 and 11 of the vertical transverse
walls of the crate. In this way, each hori-
zontal partition or shelf can be rigid from
one end to the other, for the full length of the
crate, even in a crate having a middle ver-
tical partition, inasmuch as the horizontal
shelf or partition is insertable horizontally
and removable horizontally, thereby obvi-
ating the necessity of any construction where-
65 by such a horizontal partition or shelf may

be inserted downwardly in the crate, or might
be removable upwardly therefrom. The
cleats 8, as stated, prevent endwise displace-
ment of the horizontal shelves or partitions,
but do not prevent these shelves from being
lifted slightly and then removed endwise or
longitudinally and bodily from one end of the
crate. When the crate is entirely loaded, the
arrangement is such that each tier of boxes
or baskets is practically held down in place,
so that the said horizontal shelves or parti-
tions formed by the strips 7 and cleats 8 can-
not rise enough to permit the horizontal
shelves or partitions to slide out endwise. In
this way, a two-story crate, or even a three-
story crate or greater, is provided in an eco-
nomical and satisfactory manner, by a con-
struction that permits easy loading and un-
loading of the crate, but which at the same
time insures the requisite rigidity and
strength thereof.

It will also be seen that a top wall 12 is
provided for the crate, to be secured in any
suitable or desired manner, after the crate is
loaded.

What I claim as my invention is:

1. In combination, a shipping crate having
side and bottom walls and vertical end walls,
said end walls having openings therein, and a
horizontal partition or shelf removably
supported in said openings by the end walls,
said horizontal partition or shelf being of a
width to move horizontally in the plane
thereof into the crate, through an end-wall
opening, and to be removed horizontally in
said plane through said opening, said parti-
tion or shelf having space below and above
for fruit or similar receptacles, the shelf be-
ing removable through an end wall of the
crate, as stated, after the load on the shelf is
removed upwardly to thereafter permit up-
ward removal of the load below the shelf.

2. A structure as specified in claim 1, said
crate having a vertical transverse middle par-
tition having an opening therein for the mid-
dle portion of said horizontal partition or
shelf, whereby the latter is supported at its
ends and at its middle.

3. A structure as specified in claim 1, said
horizontal partition or shelf having its ends
provided underneath with transverse cleats,
and said end walls having means providing
supporting edges engaging the under side
of the shelf immediately inside of said cleats,
whereby a slight lifting of one end of the
shelf is necessary for the endwise removal
thereof from the crate.

4. A structure as specified in claim 1, said
shelf comprising a plurality of parallel flat
strips spaced apart, with underneath cleats
connecting together the end portions of said
flat strips, whereby the shelf is of maximum
width throughout its length, and is of less
width than the distance between the sides of
the crate.

5. A structure as specified in claim 1, the relative formation of said crate and horizontal shelf being such as to preclude removal of the shelf upwardly from the top of the crate.

Specification signed this 30th day of October, 1930.

WILLIAM E. DALY.
